SELF-CONTAINED FILM PROJECTION CABINET

Edwin Busch, 1815 Seminole, Saginaw, Mich. 48603

Filed Feb. 15, 1966, Ser. No. 1,049

Term of patent 14 years

(Cl. D61—1)

Fig. 1

Fig. 2

Fig. 3

Fig. 4

Fig. 5

FIG. 1 is a front and top perspective view of a self-contained film projection cabinet, showing my new design; FIG. 2 is a front elevational view;

FIG. 3 is a top plan view;

FIG. 4 is a side elevational view, the opposite side being substantially a mirror image thereof; and

FIG. 5 is a bottom plan view thereof.

I claim:

The ornamental design for a self-contained film projection cabinet, substantially as shown and described.
